DES. 2222

Samuel M. Richardson, of New York, N.Y.

Letters Patent No. 9222 Dated March 21-1865.

Design for the cases and nosings of locks.

The schedule referred to in these Letters Patent and making part of the same,

To all whom it may concern:

Be it known that of Samuel M. Richardson, of the City and State of New York, have invented or produced a new and original Design for lock Cases and Nosings, and to hereby declare the following to be a full and clear description of the said design, reference being had to the annexed drawing making part of this specification, wherein-

Fig. 1, an elevation of the lock case and nosing representing the ornamental design of the same, and

Fig. 2, a section through the nosing at the line A-A.

The object of this design is to produce an ornamental lock case and nosing that is capable of being applied to either side of the door, or the nosing set with either end upwards so as to be available with the reversible or "Janus-faced locks."

The character of my said design will be understood from the drawing, and the same consists in a curved or arched form given to the outline of the nosing or lock case, whereby the general appearance of a shield is obtained. This ornamental configuration is

shown at Fig. 1.

DES. 2222

2

I make use of an ornamental head or moulding around
the edge of the moring or lock case, and this head is shown sectionally
in fig 2; The ornamental outline of the head projects in the form of
a flange from the box portion as shown in fig 1.

What I claim and desire to secure by letters Patent is the design
of the ornamental lock case or moring as represented.

Dated this twenty first day of October, 1865.
